UNITED STATES PATENT OFFICE.

DONALD BARNS MORISON, OF HARTLEPOOL, ENGLAND.

AIR AND LIKE PUMP.

No. 894,031.

Specification of Letters Patent.

Patented July 21, 1908.

Application filed May 18, 1907. Serial No. 374,389.

To all whom it may concern:

Be it known that I, DONALD BARNS MORISON, a subject of the King of Great Britain and Ireland, residing at Hartlepool, in the county of Durham, England, have invented Improvements in Air and Like Pumps, of which the following is a specification.

This invention relates to air and like pumps of the valveless bucket type in which discharge of the contents of the working cylinder takes place at the end of the upstroke—or of one stroke—and in which at the end of the downstroke—or reverse stroke—the contents or part thereof, of the lower or corresponding end of the pump are forced through an annular passage and through one or more ports in the cylinder walls into the space above or at one side of the bucket, and it has for its object to improve such pumps so as to obtain a higher duty from them by increasing the amount of fluid discharged for each double stroke.

The invention consists in the construction, and method of working, of a pump of the kind referred to, according to which on the downstroke—when the pump is of the vertical type—or on one stroke, say the instroke—when the pump is of the horizontal type—air or other gas, or air and water, or any mixture of fluids which are, in the main, elastic, are drawn through a port controlled by a valve into the cylinder above or at one side of the valveless bucket, while air or water or other fluid or fluids which have previously entered the lower or opposite end of the pump cylinder are, towards the end of the down stroke or instroke, subjected to pressure by the descending or inwardly moving bucket and forced by it out of the base or inner end of the pump into a space or passage or passages outside of or formed in the cylinder wall and thence into the space above or at the outer side of the bucket, thereby adding to the weight of fluid discharged on the next upstroke or outstroke of the bucket and materially increasing the duty of the pump.

Pumps designed to work in the manner described can be constructed in various forms.

In the accompanying illustrative drawings, Figure 1 shows in central vertical section, one construction of vertical air pump embodying the present invention and specially intended for use as the air pump of

condensing apparatus. Fig. 2 is a sectional detail view showing a modification. Fig. 3 is a similar view to Fig. 1, and Fig. 4 a sectional plan on the line A A of Fig. 3, showing a modified construction of vertical air pump. Figs. 5 to 8 inclusive, show in vertical section, other modified constructions of air pumps of the vertical type.

In Fig. 1, *a* is the pump barrel or cylinder, and *b* the valveless bucket which is reciprocated therein from above by the rod *d*. *c* is a suction chamber below the cylinder *a*. Surrounding the lower portion of the pump cylinder *a* is an annular passage *e* which communicates with the lower end of the pump cylinder at *e*¹ and also through the ports *f* with the interior of the cylinder at a higher level. The pump is provided with head or discharge valves *g* and in the base of the pump are foot valves *h* of which one is shown. These foot valves may be arranged all round the base of the pump and serve to admit air and water from the suction chamber *c* to the interior of the cylinder *a* on the upstroke of the bucket *b*.

Suitably disposed in the cylinder wall are ports *k* through which air can flow into the cylinder above the bucket during the downstroke of the latter. The air enters the pump casing through the inlet *m* along with water which flows into the suction chamber *c*, and on its way to the ports *k* it flows through a passage *o* and past an air valve *n* which rises automatically when the pressure in the pump cylinder *a* becomes less than that in the passage *o* and falls automatically on to its seat on any rise of pressure in the portion of the cylinder above the bucket *b*. Although a single air valve is referred to, any desired number of such valves may be used.

The action of the pump is as follows:—On the downstroke of the bucket *b* a diminution of pressure takes place in the cylinder *a* above the bucket until the latter passes the air inlet ports *k* through which air is then drawn into the cylinder until the ports *f* are uncovered. Meanwhile the air and water drawn through the foot valves *h* into the lower end of the pump cylinder *a* during the previous upstroke are being subjected to pressure and the air thereby reduced in volume, and, as soon as the bucket uncovers the ports *f*, the air and water are,

in great part, forced through the annular passage *e* and through the ports *f* into the cylinder *a* above the bucket *b*, the air valve *n*, or each air valve, at once closing automatically. During the upstroke of the bucket, the air valve or valves remain closed, and the air above the bucket is compressed and discharged through the head valves *g* at the end of the stroke, together with the water, with the exception of an amount thereof equal to the clearance space that is left between the top of the cylinder *a* and the top of the bucket *b* at the end of the upstroke of the latter and which, as a rule, will be fully occupied with water. During the upstroke, more air and water are drawn into the lower end of the pump cylinder *a* through the foot valves *h* which close at the end of the upstroke. The cycle is then repeated.

The air valve *n*, or each air valve, can be of any suitable form, and is arranged in a chamber provided with a removable door *r* for facilitating its examination and removal. In the example now being described, the air valve is shown as a light spring metal flap valve. The said valve may be water sealed, either by water drawn in by the foot valves *h*, or by water independently supplied, as for example by the pipe *y*.

Instead of forcing fluid from the base of the pump cylinder *a* to the space above the bucket *b* by way of an annular passage such as *e*, grooves or open channels of suitable length and suitably spaced, may, as shown in Fig. 2, be formed in the inner surface of the cylinder wall for the purpose mentioned.

In the construction of pump shown in Fig. 1, the ports *k* are at such a height in the pump cylinder that they are covered by the bucket *b* at the end of the upstroke thereof. The said ports may however, if desired, and in some cases can, with advantage, be placed at a lower level so that, after being covered by the bucket on its upstroke, they will be again uncovered by such bucket just as the same reaches the top of its stroke, when they will therefore be in free communication with the lower portion of the pump cylinder which is then filled with air—or air and water—at a pressure equal to or less than the pressure in the air pump suction pipe and passage *o*, so that the fluid which the ports contain will not seriously affect the volume of air drawn through the valve *n*, during the next downstroke of the bucket. Such an arrangement is illustrated in Fig. 3 wherein the bucket *b* is shown at the top of its upstroke and the ports *k* in free communication with the pump cylinder *a* below the bucket. The foot valves *h* in this arrangement are shown disposed at the side of the pump cylinder, and the air valves *n*, of which several are shown in Fig. 4, are of the disk type.

Fig. 5 shows an air pump in which the

bucket *b* is driven from below and in which there are no foot valves and only one admission port or set of ports *k*. This type of pump is specially suitable for condensing plants in which the water of condensation is drawn from the condenser by an independent pump and in which the pump, as illustrated, draws only vapor and air, the sealing and cooling water, when such is required, being admitted to the pump cylinder *a*, as through a pipe *y* above the valve or valves *n*, or otherwise, as may be desired. The single set of admission ports *k* is controlled by the valve or valves *n* which serves or serve to admit fluid to the cylinder above the bucket *b* during a considerable portion of the downstroke and to admit fluid to the cylinder below the bucket at the end of the upstroke. In other respects, the operation of such a pump is substantially like that of the pump shown in Fig. 1, the fluid being put under pressure in the lower end of the pump cylinder and forced into the space above the bucket at the end of the downstroke after the portion of the cylinder above the bucket has already been filled with vapor and air by suction.

Fig. 6 shows an air pump in which water, with or without air, is admitted to the annular passage *e* through a foot valve or valves *h* arranged outside the cylinder *a* and between the said chamber or passage and the inlet *m*, the pump being provided with one or more air inlet ports *k* may be controlled by an air valve *n* as in the other arrangements herein-before described.

In order that the pressure in the lower end of the pump cylinder *a* may not at any time exceed a safe limit, one or more relief valves such as shown in Figs. 7 and 8 may be fitted. In Fig. 7, a spring loaded relief valve *q* is arranged to discharge by a passage *w* into the suction chamber *e*. In Fig. 8, the discharge takes place through a passage *u* into the upper part of the pump cylinder *a*, or by a pipe *x* into the delivery chamber *v*; or the discharge may be otherwise disposed of as desired. Thus, the relief valve *q*, may, as indicated in Fig. 3, be placed in the bucket *b* and be suitably loaded, as by a spring, to lift only with abnormal pressure.

Although the drawings only show pumps of the vertical type, the pumps may be otherwise disposed; the valves may also be of any suitable design and be arranged as may be most convenient in each case.

A pump constructed according to the present invention may be used either as a single stage air pump, or as the first or second stage pump of a two stage arrangement. Also, it may be employed for dealing with any elastic fluid, or mixture of fluids mainly elastic. When the fluid required to be pumped is wholly elastic, as for example in the case of a dry air pump for a steam condensing plant.

water for bucket sealing or clearance filling purposes, may be admitted in the manner hereinbefore described, but it is not an essential part of the invention that water or other sealing liquid be employed.

Throughout this specification the term air is used to express either dry air or air wholly or partly saturated with water vapor. In air pumps for condensing plants, the water vapor may constitute a large proportion of the fluid which enters the pump. Also, in the claims, it is to be understood that the terms downstroke and upstroke are to be understood as not limiting the claims to pumps of the vertical type but are intended to respectively include the terms instroke and outstroke, as in the case of pumps of the horizontal type.

What I claim is:

1. An air or like pump comprising a cylinder, a bucket arranged to reciprocate therein, means for admitting fluid to the upper portion of said cylinder during the downstroke of the bucket and while its lower portion is closed by said bucket, a valve controlled inlet independent of said bucket for admitting fluid to the lower end of said cylinder, a valveless passage for placing the upper and lower portions of said cylinder at opposite sides of said bucket in communication with each other when said bucket arrives near the end of its downstroke and whereby fluid will then be forced by said bucket from the lower side to the upper side thereof, and a delivery outlet and valve whereby the combined fluids can be discharged from the upper portion of said cylinder on the next upstroke of the bucket.

2. An air or like pump comprising a cylinder and a reciprocatory bucket therein, said cylinder having an inlet for admitting fluid to its upper end portion during the downstroke of the bucket and while its lower portion is closed by said bucket, an automatic non-return valve for controlling the flow of fluid through said inlet into said cylinder, a valveless passage formed in the wall of said cylinder whereby the two portions of the cylinder above and below the bucket will be placed only in communication with each other when the bucket arrives near to the end of its downstroke, and a fluid delivery outlet and valve at its upper end.

3. An air or like pump comprising a cylinder and a reciprocatory bucket therein, said cylinder having separate inlets for admission of fluid to the upper and lower end portions of said cylinder, automatic non-return valves for both fluid inlets, a valveless connecting passage formed in the cylinder wall whereby the two portions of the cylinder at opposite sides of said bucket will, when the bucket arrives near to the end of its downstroke, be placed in communication with each other through ports that are located between the separate

fluid inlets, and a delivery outlet with valve whereby fluid can be discharged from said cylinder at each upstroke of the bucket.

4. An air or like pump comprising a cylinder and a bucket arranged to reciprocate therein, said cylinder having a fluid inlet with a non-return valve arranged to admit fluid to the lower portion of said cylinder during the upstroke of said bucket, a fluid inlet with valve arranged to admit fluid to the upper portion of said cylinder during the downstroke of said bucket, a fluid delivery outlet with controlling valve at the upper end of said cylinder, and a valveless passage communicating with the interior of said cylinder through an annular row of ports arranged between the lower and upper fluid inlets and through which fluid will be forced from the lower portion of the cylinder to the upper portion thereof when the bucket arrives near the end of its downstroke.

5. An air or like pump comprising a cylinder and a bucket arranged to reciprocate therein, said cylinder having a fluid inlet with controlling valve arranged to admit fluid to the lower portion of said cylinder during the upstroke of said bucket, a fluid inlet with controlling valve arranged to admit fluid to the upper portion of said cylinder during the downstroke of said bucket, a fluid delivery outlet with controlling valve at the upper end of said cylinder, and a valveless passage formed in the cylinder wall and communicating with the interior of said cylinder through an annular row of ports arranged between the lower and upper fluid inlets and through which fluid will be forced from the lower portion of the cylinder to the upper portion thereof when the bucket arrives near the end of its downstroke.

6. An air or like pump comprising a cylinder and a bucket arranged to reciprocate therein, said cylinder having a fluid inlet with controlling valve arranged to admit fluid to the lower portion of said cylinder during the upstroke of said bucket, a fluid inlet with controlling valve arranged to admit fluid to the upper portion of said cylinder during the downstroke of said bucket, a fluid delivery outlet with controlling valve at the upper end of said cylinder, and a valveless passage communicating with the interior of said cylinder through an annular row of ports arranged between the lower and upper fluid inlets and through which fluid will be forced from the lower portion of the cylinder to the upper portion thereof when the bucket arrives near the end of its downstroke, the fluid inlets to the upper and lower ends of said cylinder being in communication with an inlet branch common to them.

7. An air or like pump comprising a cylinder and a bucket arranged to reciprocate therein, said cylinder having a fluid inlet with controlling valve arranged to deliver

fluid to the lower portion of said cylinder during the upstroke of said bucket, a fluid inlet with controlling valve arranged to deliver fluid to the upper portion of said cylinder during the downstroke of said bucket, said inlet being arranged to be uncovered and placed in communication with the lower portion of said cylinder when the bucket is at the end of its upstroke, a fluid delivery outlet with controlling valve at the upper end of said cylinder, and a passage communicating with the interior of said cylinder through an annular row of ports arranged between the lower and upper fluid inlets and through which fluid will be forced from the lower portion of the cylinder to the upper portion thereof when the bucket arrives near the end of its downstroke.

8. An air or like pump comprising a cylinder and a bucket arranged to reciprocate therein, said cylinder having a fluid inlet controlled by a valve arranged to admit fluid to the lower portion of said cylinder during the upstroke of said bucket, a fluid inlet with controlling valve arranged to admit fluid to the upper portion of said cylinder during the downstroke of said bucket, a fluid delivery outlet with controlling valve at the upper end of said cylinder, and a valveless connecting passage communicating with the interior of said cylinder through an annular row of ports arranged between the lower and upper fluid inlets and through which fluid can be forced from the lower portion of the cylinder to the upper portion thereof when the bucket arrives near the end of its downstroke, the fluid inlet to the lower end portion of the cylinder being arranged to deliver into said connecting passage.

40 9. An air or like pump comprising a cylinder and a bucket arranged to reciprocate therein, said cylinder having a fluid inlet with controlling valve arranged to admit fluid to the lower portion of said cylinder during the upstroke of said bucket, a fluid inlet with controlling valve arranged to admit fluid to the upper portion of said cylinder during the downstroke of said bucket, a fluid delivery outlet with controlling valve at the upper end of said cylinder, and a valveless passage formed in the cylinder wall and communicating with the interior of said cylinder through an annular row of ports arranged between the lower and upper fluid inlets and through which fluid will be forced from the lower portion of the cylinder to the upper portion thereof when the bucket arrives near the end of its downstroke, the fluid inlet to the lower end portion of the cylinder being directed towards said connecting passage so that fluid issuing from it will flow into said connecting passage.

10. An air or like pump comprising a cylinder and a bucket arranged to reciprocate therein, said cylinder having a fluid inlet

with controlling valve arranged to admit fluid to the lower portion of said cylinder during the upstroke of said bucket, a fluid inlet with controlling valve arranged to deliver fluid to the upper portion of said cylinder during the downstroke of said bucket, a fluid delivery outlet with controlling valve at the upper end of said cylinder, a passage communicating with the interior of said cylinder through an annular row of ports arranged between the lower and upper fluid inlets and through which fluid will be forced from the lower portion of the cylinder to the upper portion thereof when the bucket arrives near the end of its downstroke, and a safety discharge passage with loaded valve arranged to be opened only in the event of fluid in the lower part of said cylinder being subjected to undue pressure.

11. An air or like pump comprising a vertically arranged cylinder having a conical lower end with a fluid inlet in communication therewith, a fluid inlet arranged at an intermediate portion of its height and having an inwardly opening automatic valve for admitting fluid to the upper end portion of said cylinder during the downstroke of the pump, a valve controlled fluid discharge outlet at its upper end, an annular set of ports arranged between the lower end of said cylinder and the upper inlet for fluid and communicating by a valveless passage formed in the cylinder wall with the lower end of said cylinder, and a bucket having a conical lower end arranged to reciprocate in said cylinder and to open and close said ports.

12. An air or like pump comprising a vertically arranged cylinder having a conical lower end with a valve controlled fluid inlet in communication therewith and through which fluid will be admitted to said cylinder on the upstroke of the pump, a fluid inlet arranged at an intermediate portion of its height, an automatic inwardly opening valve for admitting fluid to the upper portion of said cylinder during the downstroke of the pump, a valve controlled fluid discharge outlet at its upper end, and an annular set of ports arranged between its lower end and the upper inlet for fluid and communicating by a valveless passage with its lower end, and a bucket having a conical lower end arranged to reciprocate in said cylinder and to open and close said ports.

13. An air or like pump comprising a vertically arranged cylinder having a valve controlled inlet for fluid at its lower end, a fluid inlet arranged at an intermediate portion of its height and provided with an automatic inwardly opening valve, a valve controlled fluid discharge outlet at its upper end, and an annular set of ports arranged between the lower end of said cylinder and the upper inlet for fluid and communicating by a valveless passage with the lower end of said cylinder.

inder, and a bucket arranged to reciprocate in said cylinder and to open and close said ports, said fluid inlets being connected to an inlet branch common to them.

- 5 14. An air or like pump comprising a cylinder having a bucket arranged to reciprocate therein, upper and lower inlets for fluid each controlled by an automatic inwardly opening valve, and a valveless passage 10 adapted to establish communication between the upper and the lower portions of said cylinder, the communication with the said upper portion being by way of a set of ports con-

trolled by said bucket and located intermediate between the said upper and lower inlets for fluid, and a loaded relief valve and passage arranged in said bucket to prevent undue fluid pressure in the lower end of said cylinder on the downstroke of said bucket.

Signed at Hartlepool, in the county of 20 Durham, England, this sixth day of May, 1907.

DONALD BARNS MORISON.
